[57] CLAIM

The ornamental design for a lens cover for emergency warning light, as shown and described.

DESCRIPTION

FIG. 1 is a perspective view of a lens cover for emergency warning light embodying our new design, a fragmentary automobile and emergency warning light being shown in broken lines for illustrative purposes only.

FIG. 2 is a front view of said lens cover in enlarged scale.

FIG. 3 is a top view of said lens cover in enlarged scale.

FIG. 4 is a bottom view of said lens cover in enlarged scale.

FIG. 5 is a rear view of said lens cover in enlarged scale.

FIG. 6 is a side view as seen from the left side of said lens cover in enlarged scale.

FIG. 7 is a side view as seen from the right side of said lens cover in greatly enlarged scale.
